CLAIM

The ornamental design for a boot upper, as shown and
described.

DESCRIPTION

FIG. 1 is a front left perspective view of a boot upper,
according to our design;

FIG. 2 is a top view of the boot upper of FIG. 1;

FIG. 3 is a bottom view of the boot upper of FIG. 1;

FIG. 4 is a right side view of the boot upper of FIG. 1;

FIG. 5 is a left side view of the boot upper of FIG. 1;

FIG. 6 is a front view of the boot upper of FIG. 1; and,

FIG. 7 is a rear view of the boot upper of FIG. 1.

The broken lines in the drawings illustrate environment and
form no part of the claimed design.
